MATERIAL LOCK FOR TUNNELS

Seth M. Goorder, Deerfield, Ill.

Application March 9, 1939, Serial No. 260,701

14 Claims.

(Cl. 61—83)

In the digging of large tunnels, such as subways for electric railways, sewers and water mains, the work of excavating must often be done in an atmosphere having a pressure of from 5 five to fifty pounds per square inch greater than the outside atmosphere. Consequently, in order to maintain continuous pressure within the tunnel, air locks must be provided for the passage of men and materials into and out of the tunnel. 10 The usual manner of removing the excavated material from a tunnel is to convey it in cars to an elevator shaft that lifts the cars to the surface of the ground. These cars, both when full and when empty, must be passed through an air lock; a common expedient being to make the 15 chamber in the air lock long enough to accommodate a string of cars. Then, when double tracks are employed, it is possible to have a string of empty cars and a string of full cars 20 in the lock chamber at the same time.

Not only is there a considerable waste of compressed air whenever one of these locks is opened but, when a complete cycle in the operation of a lock to pass cars through the same is taken into 25 consideration, it will be seen that it is slow and costly. Thus, beginning with the moving of a train of cars filled with excavated material from the tunnel into the lock chamber, the tracks through the doorway must be removed and the 30 door closed. A valve must then be opened to reduce the pressure within the lock to that of the outside atmosphere. The door between the lock chamber and atmosphere is then opened and tracks are laid through the open doorway. 35 The loaded cars are then moved to the outside over these newly laid tracks and a train of empties is run into the lock chamber. The tracks leading through the doorway to the outside are then taken up and the door closed. A valve 40 must then be opened to admit compressed air into the lock chamber and equalize the pressure between the same and the interior of the tunnel. The door on the tunnel side of the lock is then opened, the tracks are relaid in the open doorway, and the empty cars are run into the tunnel 45 to be loaded with excavated material.

While the aforesaid cycle is being carried out, two cars at a time are usually rolled upon large elevators and lifted far enough above the surface of the ground to permit them to dump their loads into waiting trucks. These elevators require as a preliminary to the starting of the tunnel itself, the sinking of a shaft of very large diameter at some location which is usually quite 50 distant from the tunnel site; involving not only

the cost of the shaft with its large elevators and the cost of digging laterally therefrom to the tunnel site, but also a very considerable expense incident to the use of the land for the shaft.

The present invention has for its primary 5 object to make it possible to move excavated material from a tunnel subway or other excavation below the surface of the earth out of the excavation in a simple manner that does away with the aforesaid costly and time-taking 10 expedients which are now commonly employed.

In carrying out my invention, instead of taking the excavated material out through the main lock between the tunnel and the outside, I cause it to flow through what may be termed an automatic air lock of its own. In its simplest form, my invention contemplates the dumping of the excavated material into a hole prepared in the bottom or the side of the tunnel; the passage of the material through the hole being controlled 20 by a sealing device that prevents loss of enough compressed air to disturb the pressure conditions within the tunnel. As the excavated material leaves the tunnel, it may move by gravity or be positively moved into the lower end of a well 25 located near the excavation and provided with suitable apparatus or mechanism for raising the excavated material to the surface.

When there is no longer any need for the well and the passage leading therefrom to the 30 tunnel, these are filled and the opening in the bottom of the tunnel is closed. The well may be of small diameter because it need not provide room for a large elevator such as is needed to carry cars up and down. For this reason the 35 well may be placed close to the tunnel or subway, and the need for a large supply tunnel between the main tunnel and the well disappears.

Thus, it will be seen that in one of its aspects the present invention may be regarded as having 40 for its object to permit the excavated material from a tunnel or the like to be successfully raised to the surface through a well of small cross sectional area lying near the tunnel.

In view of the fact that a well and its connection to the tunnel can be dug and prepared at a comparatively small cost, which is negligible compared to the cost of the usual agencies required for the same purpose, and in view of the saving in cost of operation, effected by my improved method of removing excavated material, it is quite feasible to abandon the discharge outlet and prepare another whenever the tunnel 50 has advanced so far that the transportation of the material from the point at which the exca- 55

vating is being done to the dumping point becomes greater than the cost of a new outlet.

Therefore, viewed in another of its aspects, the present invention may be said to have for 5 its object to make it possible to discharge the excavated material at points within easy reach of the advancing head of a tunnel, instead of requiring it to be conveyed throughout the entire 10 length of the completed portion of the tunnel.

10 The various features of novelty whereby my invention is characterized will hereinafter be pointed out with particularity in the claims; but, for a full understanding of my invention and of its objects and advantages, reference may be 15 had to the following detailed description taken in connection with the accompanying drawings, wherein:

Figure 1 is a vertical section taken on a plane 20 transversely to a subway which is being built underneath a city street, illustrating my improved method of handling the excavated material; Fig. 2 is a view similar to Fig. 1, showing a fragment of the tunnel at the discharge outlet, as well as the combined air lock and material-moving means in a different position than that 25 in Fig. 1; Fig. 3 is a section on line 3-3 of Fig. 1; Fig. 4 is a side view of a mutilated horizontal tube or shell through which the excavated material travels upon leaving the tunnel; Fig. 5 is a 30 side view of a movable plunger member slideable within the tube or shell of Fig. 4 to move excavated material through the latter and prevent any waste of air; Fig. 6 is a section on line 6-6 of Fig. 1, but on a much larger scale; and Figs. 35 7, 8 and 9 are sections taken respectively on lines 7-7, 8-8, and 9-9 of Fig. 1, on the same scale as Fig. 6.

In the drawings I have illustrated my invention as applied to an ordinary subway for carrying railway cars below the surface of city 40 streets and, for the sake of brevity, the detailed description will be confined thereto; it being understood that when I refer to a subway I mean to include a tunnel of any kind in the construction 45 of which the present invention would be useful.

Referring to the drawings, 1 represents the 50 well of a completed section of a subway beneath the pavement 2 of a street; the floor of the subway being indicated at 3. At a suitable point in the subway there is left in the floor a hole 4 of considerable size, the same preferably having two opposed sides sloping downwardly and toward each other to produce a hopper effect. 55 Underlying the floor, directly below the opening 4, is a horizontal tube or cylindrical shell 5, preferably slightly larger in diameter than the width of the hole at the bottom. The member 5 extends from a point somewhat inwardly from 60 the bottom of the hole 4 through the adjacent side wall of the tunnel and somewhat beyond the latter; the hole in the floor being preferably located close to one of the side walls. The top of the member 5 is cut away, as indicated at 6, 65 as best shown in Fig. 9, to provide an inlet of at least the same cross sectional area as the lower end of the opening in the floor. The extreme outer end of the member 5 is closed by an end wall 7, to prevent earth from entering from the 70 outside and, as will hereinafter appear, to insure against breaking the air seal with the member 5. The under side of the member 5 is cut away near the outer end, as indicated at 8, to substantially the same extent as at the top near the other 75 end.

Slidable within the tube or shell 5 is a compound piston composed of two similar parallel pistons 9 and 10 connected together by spacing members 11 whose outer faces preferably form part of the same cylindrical surface as the peripheries of the two pistons. The distance between the pistons 9 and 10 is about equal to the length of the excisions 6 and 8 in the member 5 so that when the compound piston occupies the position shown in Fig. 1, excavated material in the hole in the floor, as indicated at A in Fig. 1, can drop down into that part of the tubular member 5 that lies directly below the inlet opening 6 in the latter and between the two pistons. If, now, the compound piston is moved toward the left in Fig. 1, into the position indicated in Fig. 2, the material lying between the two pistons is moved by the latter directly over the discharge opening 8 and, if there be a free space below this discharge opening, into that space. 20

As best shown in Fig. 5, the pistons 9 and 10 are provided with packing rings 12 extending circumferentially of and outwardly from the same; each of these rings forming a sufficiently good seal between its pistons and any unmutilated portion of the tubular member 5 within which that piston may find itself. It will be seen that in normal operation of the device one or the other of the pistons is always surrounded by an unmutilated part of the member 5, so that 30 the only air that can escape is that which is contained in the excavated material and that which can get past one of the piston sealing rings; both being of negligible value. The wall 7 at the outer end of the member 7 is so placed 35 that in the event of a break in the connection between the plunger and the air engine, the plunger cannot shoot outward far enough to allow the inner of the two pistons to move past the inner end of the opening 8 and break the seal. 40

As best shown in Figs. 5 and 6, the piston 10 has fixed thereto a long section 14 of a cylindrical shell of a diameter such as to make it a sliding fit within the tubular member 5. The length of the part 14 and its circumferential 45 width are such that when the piston device is moved into the unloading position indicated in Fig. 2, the part 14 closes the opening 6 in the top of the tubular member 5 and prevents material in the opening 6 from dropping down until 50 the piston is again brought back to the position it occupies in Fig. 1.

The piston device may be moved back and forth by means of any suitable motor which may be a simple air engine comprising a long cylinder 15 55 containing a piston 16 whose rod 17 extends out through one end of the cylinder and is there coupled to a short stem 18 projecting from the piston 16, underneath the baffle plate 14. This engine can readily be salvaged, along with the 60 plunger, when the outlet with which it is associated has served its purpose.

Material may be brought to the discharge point by means of suitable dump cars 19 running on suitable tracks 20 on the floor of the tunnel. 65

In order that the material brought over the discharge outlet 8 by the double piston may leave through that outlet, I form below the outer end of the tubular member 5 a chamber 21 having a bottom wall 22 that slopes downwardly 70 as it recedes from the vicinity of the tunnel. The chamber 21 communicates with or opens into the lower end of a well 24 of fairly small diameter that may open down through the outer portion of a sidewalk adjacent to the street or 75

roadway, and thus leave the roadway clear while the obstruction to the sidewalk need not interfere with normal traffic along the latter. In this well is a suitable hoisting device, shown as consisting of a bucket 25 suspended from a cable 26 which rises to the top of a superstructure 27 registering with the well and thence over suitable pulleys 28 to a suitable hoisting engine, not shown. The parts are so proportioned that when the bucket is at the bottom of the well, its top is slightly below the lower end of the sloping wall 22 and near the latter. Consequently, whenever a load of clay or the like is dumped down into the chamber 21, at a time when the bucket is down, it slides down the inclined wall or face 22 and enters the bucket. The superstructure 27 is made high enough to permit the bucket to dump its load automatically into a truck B standing beside the same.

It will be seen that, in addition to the saving in compressed air which I achieve, all excavated material may be promptly removed from the tunnel. This is due to the fact that the flow of excavated material from the tunnel to the surface 25 of the ground may be practically continuous, because the conveyor may be operated in synchronism with the material-transferring plunger or of such a type that the plunger operates continuously, with the assurance that the material moved by it will be taken away. So, also, there must be no delay in filling trucks by which the excavated material is finally hauled from the vicinity of the tunnel.

It will further be seen that I am able to avoid the long delay and expense incurred in sinking a shaft thirty or more feet in diameter at some available spot, which may be far from the tunnel location and can perhaps be obtained only by paying a high rental, and digging a special tunnel 40 to the point where the desired tunnel is to start, before actual work on the latter can begin.

In other words, by my invention I am able to avoid the long delay in starting work on the tunnel itself, after actual digging has actually started, which often occurs in large cities, and the great expense caused by the delay and the preliminary construction and excavation which become unnecessary under my method; to clear away material as it is excavated and without waiting until an air lock may be opened; to reduce the distance through which the excavated material must be hauled while underground; and to effect a considerable saving in the amount of compressed air needed to maintain the required pressure in the tunnel.

It should perhaps be noted that the provision made in the illustrated form of my invention for salvaging the air engine and the reciprocable plunger comprises an opening in the floor above the engine. This opening may be of the same width, lengthwise of the tunnel, as the opening 4 and may, in effect, be a continuation of the latter. However, the opening 13 in the floor above the engine and the opening 4 are conveniently separated by a floor fragment 23 which serves to provide a setting for the tubular member 5. After the engine and the plunger are removed, the openings 4 and 23 may be filled in while the tubular member 5 remains in place.

It will be understood that in its broad aspects the invention is not confined to a particular location of the outlet in the tunnel wall, it being sufficient that the outlet be at such a level that the excavated material may successfully be fed into the same. Thus, while an opening in the

floor permits material to be dumped into the same from cars running on tracks laid on the floor of the tunnel, it makes it necessary to have a well deep enough to extend considerably below the bottom of the tunnel. An outlet higher up may be more suitable for other material-delivering means, while permitting the use of a shallower well.

It will also be seen that my improved material transferring device may be used for other purposes than removing excavated material since, by modifying it slightly, it may serve to deliver material from the outside into the tunnel. Thus, for example, mixed concrete or the solid constituents thereof may be brought into the tunnel in this manner.

I claim:

1. Means for removing excavated material from a tunnel comprising a well extending from the surface of the ground at any desired distance from the tunnel to a point below the level of the bottom of the tunnel; material-conveying means in the well to raise material entering the lower end of the well to the surface, a passage extending from the lower end of the well into the tunnel; and means, including a combined material-transfer device and air lock, to move material from the tunnel end of the passage into the lower end of the well.

2. The method of removing excavated material from a long tunnel in the digging of the same, which consists in digging a series of wells distributed along and located at any desired distance from the tunnel, each well extending to a depth below the bottom of the tunnel, creating a passage leading from the lower end of each well up into the tunnel as the construction and the latter progresses; operating in conjunction with each passage a combined material-transferring and passage sealing means to move toward the corresponding well excavated material dumped into the tunnel end of the passage, and conveying the excavated material to the top of the well.

3. Means for removing excavated material from a tunnel comprising a well extending from the surface of the ground at any desired distance from the tunnel to a point below the level of the bottom of the tunnel; material-conveying means in the well to raise material entering the lower end of the well to the surface, the tunnel having a hole in the bottom, there being a passage extending from the lower end of the well to a point below and communicating with the tunnel; and means, including a reciprocable material-transfer device slideable in said passage for alternately receiving material through said hole and closing communication between the latter and said passage, to move material from the tunnel end of the passage into the lower end of the well.

4. The combination with a tunnel that is being excavated, of a well extending from the top of the ground to a level considerably below the bottom of the tunnel, the well being connected to the tunnel by a passage opening into the latter through the level of the bottom thereof, a conveyor in the well for elevating material, and means in the passage to receive excavated material deposited in the tunnel end and move such material toward the well and discharge it while sealing the passage sufficiently to prevent the escape therethrough of objectionable amounts of air when the air in the tunnel is under pressure greater than that of the outside atmosphere.

5. The combination with a tunnel that is being

- excavated, of a well extending from the top of the ground to a level considerably below the bottom of the tunnel, the well being connected to the tunnel by a passage opening into the latter through the level of the bottom thereof, a conveyor in the well for elevating material, and means in the passage to receive excavated material deposited in the tunnel end and move such material toward the well and discharge it while sealing the passage sufficiently to prevent the escape therethrough of objectionable amounts of air when the air in the tunnel is under pressure greater than that of the outside atmosphere, the passage having at its outer end a downwardly inclined bottom wall in position to receive the discharged material and guide it to the conveyor.
6. The combination with a tunnel that is being excavated, of a well extending from the top of the ground to a level considerably below the level of the bottom of the tunnel, a material-elevating conveyor in the well, the well being connected to the tunnel by a passage opening into the latter through the bottom thereof and so positioned that material entering that section adjacent to the well flows by gravity into the conveyor, a horizontal reciprocable plunger fitting slidably in that section of the passage below the opening into the tunnel and comprising two pistons spaced apart from each other in the lengthwise direction to provide between them a material-receiving chamber open at the top and at the bottom, and means to shift the plunger from a position in which material may drop down into said chamber from within the tunnel to a second position in which the material may drop from said chamber into the first-mentioned section of the passage.
7. The combination with a tunnel that is being excavated, of a well extending from the top of the ground to a level considerably below the level of the bottom of the tunnel, a material elevating conveyor in the well, the well being connected to the tunnel by a passage opening into the latter through the bottom thereof and so positioned that material entering that section adjacent to the well flows by gravity into the conveyor, a horizontal reciprocable plunger fitting slidably in that section of the passage below the opening into the tunnel and comprising two pistons spaced apart from each other in the lengthwise direction to provide between them a material-receiving chamber open at the top and at the bottom, and means to shift the plunger from a position in which material may drop down into said chamber from within the tunnel to a second position in which the material may drop from said chamber into the first-mentioned section of the passage, said plunger having at one end part that closes the opening in the bottom of the tunnel when said plunger is in said second position and until the plunger is again retracted far enough to cause the piston at the other end to form a seal within the passage.
8. The combination with a tunnel that is being excavated, of a well extending from the top of the ground to a level considerably below the level of the bottom of the tunnel, a material elevating conveyor in the well, the well being connected to the tunnel by a passage opening into the latter through the bottom thereof and so positioned that material entering that section adjacent to the well flows by gravity into the conveyor, a horizontal reciprocable plunger fitting slidably in that section of the passage below the opening into the tunnel and comprising two pistons spaced apart from each other in the lengthwise direction to provide between them a material-receiving chamber open at the top and at the bottom, and an air engine located below the floor of the tunnel to shift the plunger from a position in which material may drop down into said chamber from within the tunnel to a second position in which the material may drop from said chamber into the first-mentioned section of the passage.
9. The combination with a tunnel that is being excavated, of a well extending from the top of the ground to a level considerably below the level of the bottom of the tunnel, a material-elevating conveyor in the well, the well being connected to the tunnel by a passage opening into the latter through the bottom thereof and so positioned that material entering that section adjacent to the well flows by gravity into the conveyor, a horizontal cylindrical shell forming the inner section of the passage, said shell having in the top an opening registering with the opening in the bottom of the tunnel and an opening in the bottom above the first-mentioned section of the tunnel, a horizontal reciprocable plunger fitting slidably in said shell and comprising two pistons spaced apart from each other a distance less than the distance between the said openings in the shell, to provide between them a material-receiving chamber open at the top and at the bottom, and means to shift the plunger from a position in which material may drop down into said chamber from within the tunnel to a second position in which the material may drop from said chamber into the first-mentioned section of the passage.
10. The method of removing excavated material from a long tunnel in the digging of the same, which consists in digging a series of wells distributed along and located at any desired distance from the tunnel, creating a passage leading through a wall of the tunnel into the lower end of each well as the construction and the latter progresses; operating in conjunction with each passage a combined-material-transferring and passage sealing means to move toward the corresponding well excavated material dumped into the tunnel end of the passage, and conveying the excavated material to the top of the well.
11. Means for removing excavated material from a tunnel comprising a well extending from the surface of the ground at any desired distance from the tunnel to a point below the level of the top of the tunnel; material-conveying means in the well to raise material entering the lower end of the well to the surface, the tunnel having a hole in a wall above the bottom of the well, there being a passage extending from the well to said hole and means, including a reciprocable material-transfer device slidable in said passage for alternately receiving material through said hole and closing communication between the latter and said passage, to move material from the tunnel end of the passage into the well.
12. The combination with a tunnel that is being excavated, of a well extending from the top of the ground to a level considerably below the top of the tunnel, the well being connected to the tunnel by a passage opening into the latter through a wall thereof, a conveyor in the well for elevating material, and means in the passage to receive excavated material deposited in the tunnel end and move such material toward the well and discharge it while sealing the passage.

sufficiently to prevent the escape therethrough of objectionable amounts of air when the air in the tunnel is under pressure greater than that of the outside atmosphere.

- 5 13. The combination with a tunnel that is being excavated, of a well extending from the top of the ground to a level considerably below the top of the tunnel, the well being connected to the tunnel by a passage opening through a
- 10 wall thereof, a conveyor in the well for elevating material, and means in the passage to receive excavated material deposited in the tunnel end and move such material toward the well and discharge it while sealing the passage sufficiently
- 15 to prevent the escape therethrough of objectionable amounts of air when the air in the tunnel is under pressure greater than that of the out-

side atmosphere, the passage having at its outer end a downwardly inclined bottom wall in position to receive the discharged material and guide it to the conveyor.

- 5 14. Means for removing excavated material from a tunnel comprising a bore extending from the surface of the ground at any desired distance from the tunnel to a point below the level of the bottom of the tunnel; material-conveying means in the bore to raise material entering the latter to the surface, a passage extending upwardly from the bore into the tunnel; and means, including a combined material-transfer device and air lock, to move material from the tunnel end of the passage into the bore.

35
SETH M. GOODER.
